Samuel Austin Greene

Inventor:

UNITED STATES PATENT OFFICE.

LEMUEL AUSTIN GREENE, OF GREENVILLE, SOUTH CAROLINA.

CLASSIFICATION AND GRADING OF COTTON.

1,286,589.

Specification of Letters Patent.

Patented Dec. 3, 1918.

Application filed April 30, 1917. Serial No. 165,602.

To all whom it may concern:

Be it known that I, LEMUEL AUSTIN GREENE, a citizen of the United States, a resident of the city of Greenville and county 5 of Greenville and the State of South Carolina, have invented certain new and useful Improvements Pertaining to Classification and Grading of Cotton. The following specification and accompanying drawing are 10 a full description.

My invention embraces the manner of assembling a series of standard grades of cotton in a cabinet having a transparent cover, also having nine receptacles for the purpose 15 of containing nine duplicates of the standard grades of cotton now being issued by our Government, embracing the nine leading white grades of cotton; also nine other receptacles for the purpose of containing 20 the relative tinges of the standard grades of white cotton. The above eighteen grades are all listed by the exchanges, and each has a specific value on the daily market. It is also the purpose to have a central receptacle for the purpose of displaying the 25 length of staple.

It is a well known fact that different lights or reflections from different walls or buildings, also the bright sun light causes cotton 30 to appear as a different quality or grade. A cloudy day, or a day when the ground is covered with snow, will materially affect the appearance of cotton to an untrained eye. It requires long experience and much practice 35 for a buyer to locate the correct grades of cotton under these and other existing circumstances.

It is the purpose of the inventor to arrange in a convenient manner the eighteen 40 listed grades of cotton embracing the nine standard Government grades in a cabinet under a transparent cover for the protection of the fixed grades while in use, and not interfere with the work of matching any 45 sample of cotton under any circumstances or any change of light or reflection, because the same reflections are alike on the fixed grades and the sample to be graded. It is not possible for the cotton growers to become 50 expert cotton graders, because the mind's eye cannot maintain these reflections of color and leaf for lack of continual practice, as is the case with a cotton buyer.

In the drawings,

Figure 1 is a top plan view of my invention. 55

Fig. 2 is a central, vertical section of the grader taken on the line 2—2 of Fig. 1; and Fig. 3 is a bottom plan view.

The outer casing is formed by two concentric circular rims, 1 and 2, preferably 24 and 18 inches, respectively, in diameter, connected by an annular plate 3. The second inner casing is formed by two smaller rims, 4 and 5, preferably 12 and 4 inches in 60 diameter, respectively, concentric with those first named and with each other and connected by an annular plate 6. Nine equally angularly spaced radial ribs 7 connect the innermost with the outermost rims, thereby 65 dividing the zone formed by the rims 1 and 2 into nine compartments, 8, that by the rims 2 and 4 into nine compartments, 9, and that by the rims 4 and 5 into nine compartments, 10. The inner circular rim 5 forms 70 the wall of a central compartment 11 into which telescopes a removable bottom 13. The glass plate 12 is superposed upon the parts thus constructed, which are preferably made of paste board. This plate 12 protects 75 the contents of the grader from being injured by usage, and from dust and other sources of damage.

The outer compartments 8 are adapted to receive the duplicates of the nine Government standard grades of cotton. The mates of these official grades, found in the tinges and stained cotton as listed by the cotton exchanges, are placed in compartments 10. In the compartment 11 are displayed the 80 different lengths of fiber and explanations of the means for testing the same.

The cotton to be tested is placed from beneath between the corresponding compartments 8 and 10 in the corresponding receptacle 9 and compared with the samples in the compartments 8 and 10. 95

Having described my invention: what I claim as new and desire to secure by Letters of Patent is:

1. A cotton classifier consisting of a case provided with a plurality of compartments adapted to receive samples of cotton, said compartments being divided into two equal series, separated by a space permitting the 100 viewing therethrough of samples to be classified.

2. A cotton classifier consisting of a case

provided with a plurality of compartments divided into two equal circular series separated by a space permitting the viewing therethrough of samples to be classified and 5 a central pocket about which the two circular series are arranged.

3. A cotton classifier consisting of a case provided with a plurality of compartments adapted to receive samples of cotton, said 10 compartments being divided into two equal

circular series, separated by a space permitting the viewing therethrough of samples to be classified.

In testimony whereof I affix my signature in presence of two witnesses, this the 24th 15 day of March, 1917.

LEMUEL AUSTIN GREENE. [L. S.]
